UNITED STATES PATENT OFFICE

1,984,098

TIME FUSE FOR PROJECTILES

André Varaud, Geneva, Switzerland

Application August 30, 1933, Serial No. 687,517
In Switzerland September 10, 1932

6 Claims. (Cl. 102—36)

The invention relates to a device for locking the timing position of the driving member of the timing means in a mechanical fuse for projectiles.

5 The annexed drawing illustrates, by way of example a form of construction of the invention.

Fig. 1 is an axial section of the improved fuse and Fig. 2 is a section on line II—II of Fig. 1 10 and shows the locking device in plan.

In the fuse represented, the timing is effected in known manner by winding the spring of the clockwork movement partly illustrated in the lower part of Fig. 1, this being effected 15 by rotating the cap 1 by means of a key which rotatory movement is transmitted to the clock-work movement by means of the central shaft 2, which terminates in a key 3 engaging in a corresponding rectangular opening of a disc 4 which in turn acts on the members to be driven.

20 In the example represented the disc 4 is coupled to a second disc 5 and possesses two lugs 6, extending horizontally above the disc 5 and at a certain distance from the latter.

25 These lugs 6 together with the disc 5 are traversed by pins 7 serving as pivotal axes for centrifugal rockers or weights 8 each provided with a tooth 9 adapted to engage with an interiorly toothed crown formed inside the body

30 11 of the fuse.

Springs 12 acting on an extension 13 of the rockers or weights 8 hold the latter in their position nearest the center, which position they will tend to leave under the effect of the centrifugal force set up on the firing of the projectile.

35 In fact, from the moment that a rotatory movement is communicated to the projectile, the rockers or weights 8 pivoting about the pins 7, will apply their respective teeth 9 against the teeth 10 and will thus lock the discs 5, 6, therefore also the timing members against a tendency to be displaced with respect to the body of the fuse in the direction of the arrow 40 14. This direction is determined, as appears from the drawing, by the direction of the inclination of the teeth 10, which should be such as to oppose the effect of irregular action which it is desired to prevent.

45 Instead of using inclined teeth, upright teeth could be used which would have the effect of providing a locking action in both possible directions of rotation. Such locking in both directions can also be obtained by providing two 50 sets of inclined teeth of opposite direction with

which two corresponding groups of centrifugal weights would co-operate.

In the example illustrated these weights are two in number, but it is evident that several pairs could be used or further that an odd number thereof could be used the minimum number of weights being besides fixed only by reasons of equilibrium, so that the case of a single weight may also be contemplated, if care is taken to provide such an arrangement of the 10 masses of the whole device altogether, that balance will be maintained.

15 In order to avoid a possible irregularity of the width of one of the teeth 10 which, for that reason, will have to be selected of very small pitch, a number of teeth can be provided with a corresponding number and arrangement of weights so that when the tooth of one of the weights completely enters one of the intervals between the teeth 10, the teeth of the one or 20 more other weights are more or less staggered from this ideal position of complete engagement.

25 The springs 12 need not necessarily be plates, but could be spiral springs or any other elastic members capable of bringing back the centrifugal weights towards the centre.

30 What I claim as my invention and desire to secure by Letters Patent of the United States is:—

1. In a time fuse for projectiles, a hollow body member having teeth formed on the interior thereof, a driving member in said body mounted for rotation relative to said body member, a centrifugally actuated element carried by said driving member, and means carried by said element adapted to engage the teeth within said body member upon the actuation of said element by centrifugal force due to rotation of said projectile when fired.

2. In a time fuse for projectiles, a hollow body member having teeth formed on the interior thereof, a driving member in said body mounted for rotation relative to said body member, a centrifugally actuated element carried by said driving member, means carried by said element adapted to engage the teeth within said body member upon the actuation of said element by centrifugal force due to rotation of said projectile when fired, and resilient means acting on 50 said element tending to maintain the means carried thereby out of engagement with the teeth in said body.

3. In a time fuse for projectiles, a hollow body member having teeth formed on the interior 55

thereof, a driving member in said body mounted for rotation relative to said body member, a weighted arm pivoted to said driving member and provided with means to engage the teeth provided in said body to lock the driving member to said body against relative rotation in at least one direction, a spring tending to maintain said arm in a position out of locking engagement with said body, said arm being susceptible to the action of centrifugal force created by rotation of the projectile when fired to overcome the action of said spring and to move into locking engagement with the teeth in said body.

4. In a time fuse for projectiles, a hollow body member having teeth formed on the interior thereof, a driving member in said body mounted for rotation relative to said body member, centrifugally actuated elements carried by said driving member, and means carried by said elements adapted to engage the teeth within said body member upon the actuation of said elements by centrifugal force due to rotation of said projectile when fired, said elements being so positioned about said driving member that when the means carried by one element is in locking engagement between two teeth of said body another of said means is approaching a similar position between two other teeth.

5. In a time fuse for projectiles, a hollow body member having teeth formed on the interior thereof, a driving member in said body mounted for rotation relative to said body member, centrifugally actuated elements carried by said driving member, means carried by said elements

adapted to engage the teeth within said body member upon the actuation of said elements by centrifugal force due to rotation of said projectile when fired, and resilient means acting on said element tending to maintain the means carried thereby out of engagement with the teeth in said body, said elements being so positioned about said driving member that when the means carried by one element is in locking engagement between the teeth of said body another of said means is approaching a similar position between two other teeth. 5

6. In a time fuse for projectiles, a hollow body member having teeth formed on the interior thereof, a driving member in said body mounted for rotation relative to said body member, a plurality of weighted arms pivoted to said driving member and provided with means to engage the teeth provided in said body to lock the driving member to said body against relative rotation in at least one direction, a spring urging each arm to a position out of engagement with said body, said arms being susceptible to the action of centrifugal force created by rotation of the projectile when fired to overcome the action of said springs and to move into locking engagement with the teeth in said body, said arms being spaced about said driving member so that when the means carried by one arm is in locking position between two teeth, the means carried by another arm is approaching locking position between two other teeth. 15 20 25 30
